ATTORNEY

UNITED STATES PATENT OFFICE

JOSEPH BECKER, OF PITTSBURGH, PENNSYLVANIA, ASSIGNOR TO THE KOPPERS COMPANY, OF PITTSBURGH, PENNSYLVANIA, A CORPORATION OF PENNSYLVANIA

COKE OVEN

Application filed June 12, 1926. Serial No. 115,445.

This invention comprehends improvements of general utility in the coke oven art; and also comprehends certain improvements especially applicable to coke ovens of the well known cross-regenerative type.

In commercial coke ovens as ordinarily constructed the combustion flues of the heating wall discharge into a common flow and equalizer flue which in ovens with vertically flued heating walls is termed the horizontal flue. It follows that while the sides of that portion of the heating wall occupied by the vertical flues are braced by the partition walls which separate them the sides of that portion of the heating wall through which the horizontal flue passes are not so braced.

Therefore the elimination of the horizontal flue from the heating wall would give the maximum strength to such wall.

My invention has for one of its objects to dispense with the horizontal flue with the heating wall and yet retain the equalizing capability of an oven provided with horizontal flues together with the capability of regulation of each combustion flue.

These results I accomplish by employing separate flow and equalizer ducts, the flow ducts being each individual to a combustion flue or a unit comprising a limited number, preferably not over two, of such flues, whereby the flow duct for one combustion flue, or unit, will be separated from its neighbor by wall structure which serves to brace that portion of the wall against strain. I then preferably locate my equalizer passages or ducts, which in order to give added strength may permissibly be of less cross-sectional area than either the flow ducts alone or the combined flow and equalizer ducts of the prior art, in some portion of the brickwork where they will not tend to weaken the wall structure. It follows that the wall structure as a whole is strengthened and its permissible height increased. Moreover, by limiting my flue unit to a pair of flues for each flow duct, the latter being connected to the former half way between them, I am enabled to obtain symmetrical flow from each flue which facilitates regulation.

In applying my invention, for instance,

to an oven of the so-called cross-over type, I may connect the flues in different walls to each other individually, or in units, as hereinbefore indicated, by individual connecting flow ducts and may interconnect the several sets of flues, or units, thus connected, by equalizer passages located at any one of a plurality of points between them. Thus, for instance, I may connect those flow ducts lying between successive oven feed openings by an equalizer passageway located in the crown of the oven whereby a single equalizer passageway serves for flues in both of the interconnected walls, and I may then complete the equalization of the several groups lying respectively between successive feed openings by connecting the groups on opposite sides of a feed opening by equalizer passageways lying within the respective heating walls and extending between adjacent flow ducts of said groups, at the level of the ordinary horizontal flue, or, between the adjacent inspection passages of the respective groups at or below the level of the highest portion of the crossover duct, or, the respective groups may be connected by equalizing passages between the tops of their adjacent flues lying on opposite sides of the respective feed openings, or I may connect all of the flues in the latter manner, dispensing with other wall equalizer connections.

As a further highly important feature of my invention I provide for equalization between all of the flow groups of the entire battery. This I may accomplish by providing equalizing connections longitudinally of the battery between the several transversely equalized sets of flues. These connections may conveniently be located in the oven top extending between equalizing passages of the wall groups or between the several crossover flow ducts themselves, and preferably at normally equi-pressure points in the latter. Further, such connection may be made to each crossover flow duct or may be made at selected intervals transversely of the battery.

In addition to the general features and objects of the invention above recited the invention has such other improvements or advantages in construction and operation as

are found to obtain in the structure and devices hereinafter described or claimed.

In the accompanying drawings, forming a part of this specification and showing for purposes of exemplification a preferred form and manner in which the invention may be embodied and practiced, but without limiting the claimed invention specifically to such illustrative instance or instances:

10 Figure 1 is a longitudinal vertical section of a portion of the battery on the line 1—1 of Fig. 3,

Fig. 2 is a horizontal section of a portion of the battery on the line 2—2 of Fig. 1,

15 Fig. 3 is a vertical section transverse of the battery through a heating wall and regenerator chambers on the line 3—3 of Fig. 1,

Fig. 4 is a longitudinal vertical section of 20 a portion of the battery on the line 4—4 of Fig. 6 showing a modified form of my invention,

Fig. 5 is a horizontal section of a portion 25 of the battery on the line 5—5 of Fig. 4,

Fig. 6 is a vertical section transverse of the battery through a heating wall and regenerator chambers on the line 6—6 of Fig. 4,

30 Figs. 7 and 8 are fragmentary vertical sections of an oven wall transversely of the battery showing further modified forms of equalizer connections between the main groups shown in Figs. 1, 2 and 3, and

35 Figs. 9 and 10 are similar views showing the same modifications applied to the individual crossovers of Figs. 4, 5 and 6.

The same characters of reference indicate the same parts in each of the several figures of the drawings.

40 Referring to Figures 1, 2 and 3 of the drawings there are illustrated views of a coke oven battery or plant of the crossover type comprising a plurality of crosswise elongated heating walls 11 and a plurality of intermediate crosswise elongated vertical

45 coking chambers 12 beneath which are the usual heavy or supporting pillar walls 13 and regenerator chambers 14 provided with the usual brickwork and communicating with the flues of the heating walls through ducts

50 15. There are also provided coke oven gas ducts 16, it being understood that the oven is operable alternatively on producer gas introduced through the appropriate regenerators of the regenerative system or by coke

55 oven gas through the ducts 16. Each coking chamber 12 is provided with the usual feed openings 18 and each heating wall is divided by a central partition wall 19 so that the two halves of the battery may operate in parallel to each other.

60 Each heating wall 11 is provided with a plurality of vertical combustion or heating flues 20 formed by partition walls 21 extending between the sides 22 of said walls. It will readily appear that these partitions 21

serve to brace the sides 22 of the wall. Each flue is provided with a port 23 in its top whose effective cross-sectional area may be regulated by a sliding brick 24 through an inspection opening 25.

70 In accordance with my present invention as exemplified in the form shown in Figs. 1, 2 and 3, I provide an individual crossover duct 30 for each of the consecutive pairs of

flues 20 where a sufficient number of such flues lie between consecutive feed openings to constitute pairs and where, as shown at

75 20', a single heating flue is segregated by a feed opening I provide an individual cross-

80 over duct 30' for such flue. It will be understood that both the pairs of flues and the single flues of a given heating wall are connected by the respective crossovers to similar

85 pairs of flues or single flues respectively in an opposite wall although it will be clear that these crossovers, if desired, may connect with similar flues in other than the op-

posite wall and still lie within the spirit 90 of my invention. Each flue of a pair of heating flues 20 communicates with the com-

mon crossover duct 30 for that pair through its port 23 and a horizontal flow passage-

95 way 31 extending between the ports of that pair to the center of which the crossover duct is connected in order that the flow from the respective flues of a pair to the cross-

100 over duct may be along symmetrical paths thus tending to equalize the flow. As will appear from an inspection of the drawings the crossover ducts for the several pairs of

105 heating flues in a given half of the heating wall will be formed into groups each group comprising those crossover ducts lying be-

110 tween consecutive feed openings 18 or be-

115 between a feed opening next the center and the central partition wall 19, or between a feed opening and an end of the wall. In order that the flow between the pairs of flues

120 of the several groups may be equalized, equalizing passageways 40 are provided in the brickwork constituting the oven top and pref-

125 erably in the plane of the oven chamber, between the crossover ducts of each group respectively, and in order that the flow be-

130 tween the several groups may be equalized I provide additional equalizing passageways

135 41 between the tops of adjacent flues of the consecutive groups. It is obvious, however, that these equalizing passageways between

140 groups may be located in any portion of the top of the oven where they will not inter-

145 fere with the feed openings. For instance, they are shown in Fig. 7, at 42, between the horizontal flow passageways 31 of adjacent

145 groups, where by reason of their diminished cross-sectional area and their location only

150 between groups, rather than between all of the flues of the groups they do not cause any substantial weakening of the wall struc-

ture.

115

120

125

130

In Fig. 8 they are shown at 43 in still a different position, that is, between inspection flues which communicate with the end flues of groups on opposite sides of a feed opening and preferably at the same level as or below the horizontal portion of the crossover duct 30.

Where a crossover duct would normally lie too close to a feed opening to permit the walls of the latter to be made of sufficient thickness I deflect said crossover as shown for instance at 32 to carry it away from said opening and since in so deflecting it a straight line communication may be afforded along the corresponding inspecting opening 25 between one of the flues of a pair and the crossover duct which would tend to shunt the normal flow from that flue and tend to disturb equalization between the flues of that pair I provide in said shunt pathway a sliding brick 33 which may be moved away from the inspection opening to permit inspection or may be moved across the same during normal operation to prevent the shunting of the flow from said flue.

By the construction hereinbefore described it is clear that I provide equalization between the flues of interconnected pairs of heating walls, respectively. In order that all of such pairs of heating walls be equalized as between themselves, thus effecting equalization of the entire battery I provide equalizing channels 45 in the oven top, longitudinally of the battery and connecting the equalizing passages 40 or the flow ducts 30 of the successive pairs of heating walls.

In the operation of the oven the flow from the flues of a pair to its crossover 30 will be equalized by the connecting passageway 31, the flow between the several pairs of a group by the equalizing passageways 40, the several groups will be equalized through the passageways 41, 42 or 43 between them, while flow between successive pairs of walls will be equalized by the equalizing channels 45. Thus complete equalization of the entire battery is provided. The portions of the walls lying between passageways 31 effectively serve to brace the wall structure and thus strengthen it.

In the form of my invention exemplified in Figures 4, 5 and 6, I provide each flue of a given heating wall with an individual crossover duct 50, comprising a horizontal portion extending over the oven chamber and vertical leg portions 51 extending downwardly from the opposite ends of the horizontal portion, each leg portion communicating through a port with a flue on opposite sides of an oven chamber respectively. The inspection passages 55 may conveniently be placed in alignment with the leg portions 51 of the crossover duct, thus obviating the necessity of extending said passages independently to the bottom of the brickwork

constituting the oven top, thereby materially increasing the strength of the walls.

Those crossover ducts which would otherwise lie too close to a feed opening 18 are deflected as shown at 56 in a manner similar to that already described with reference to Figs. 1, 2 and 3. In order to equalize the flow from the several flues of a given wall I may provide equalizing passageways 61 between the tops of each of the consecutive flues or as hereinbefore indicated such equalizing passageways may be provided in the oven top in any position where they will not interfere with the feed openings 18, for instance, as shown at 62 in Fig. 9 or at 63 in Fig. 10. In order to equalize pairs of flued walls their crossover ducts 50 are shown connected to each other longitudinally of the battery by equalizing channels 65. All of the crossover ducts may be so interconnected or such inter-connections may be made at such intervals as to insure substantially complete equalizing action.

In this modification of my invention it will be obvious that the flow in all of the flues will be equalized by the passageways 61, 62 or 63 and the flow between all of the interconnected pairs of walls by the equalizing channels 65. Since the flow ducts from the tops of the flues are of restricted cross-sectional area because they each serve only a single flue and since each is separated from the other by a substantial portion of the wall structure which serves to brace the latter great wall strength is attained.

The invention as hereinabove set forth is embodied in a particular form of construction, but may be variously embodied within the scope of the claims hereinafter made.

I claim:

1. In a coking oven, or the like, in combination: a series of alternate heat treating chambers and heating walls therefor arranged laterally of each other in a row; each of said heat treating chambers having in its top a plurality of charging openings spaced from each other; each of said heating walls comprising vertical combustion flues, the flues in each of the walls being divided into units of at least one flue each; ducts above one of said chambers individual to and communicably connecting one of said units in one of said walls with one of said units in another of said walls; equalizing passages located above said one of said chambers, each of said passages being in communication with the ducts which lie between two consecutive charging openings, respectively, to constitute groups of units respectively separated by said openings; and other equalizing passages in communication with a plurality of said groups of units separated by one of said charging openings respectively.

2. The combination as claimed in claim 1,

- in which said other equalizing passages extend through the partition walls between and are in communication with the tops of adjacent flues.
5. 3. The combination as defined in claim 1, in which still other equalizing channels are provided between and are in communication with the ducts of successive pairs of duct-interconnected flued walls.
10. 4. The combination as defined in claim 1, in which still other equalizing channels are provided between and are in communication with the ducts of successive pairs of duct-interconnected flued walls, said channels being located in the top of the battery and extending longitudinally thereof.
15. 5. In a coking oven, or the like, in combination: a series of alternate coking chambers and heating walls therefor arranged laterally of each other in a row, each of said heating walls comprising combustion flues, the flues within each of said walls being communicably connected in pairs; ducts individual to and communicably connecting one 20 of said pairs in one of said walls with one of said pairs in another of said walls; and equalizing passages through the partition walls between and in communication with adjacent flues of adjoining pairs of the flues 25 in each wall.
30. 6. The combination as defined in claim 1 and in which the flue units each comprise a pair of flues, and in which each flue of a pair of flues communicates with their said connecting duct through a flow path of substantially the same size and shape as the flow path for the other flue of the same pair.
35. 7. In a coking oven, in combination: a series of alternate coking chambers and heating walls therefor arranged laterally of each other in a row, each of said heating walls comprising a row of combustion flues, the row of combustion flues in each of the heating walls being divided into units of at 40 least one flue each and the units in each of the rows being communicably connected with the units in one of the other heating walls, respectively, for passage of combustion products from the flues of one unit into and 45 through the flues of the other unit, by ducts extending transversely of and past coking chambers intervening said units, said ducts being individual to and communicably connecting one of said units in one of the heating walls with one of said units in one of the other heating walls and being so distributed along each of the rows of flues that 50 gas-flow may be controlled through each of the units in the respective rows for their respective positions therein independently of the gas-flow through units in other positions in the same row therewith; and gas pressure 55 equalizing passages communicably connecting the respective duct-interconnected units with other duct-interconnected units which lie in relatively different positions in their respective rows, said equalizing passages being separate from and independent of the communications between the respective ducts and the flues with which said ducts communicate.
60. 8. The combination as defined in claim 7 and in which the flue units each comprise a pair of flues, and in which each flue of a pair of flues communicates with their said connecting duct through a flow path of substantially the same size and shape as the flow path for the other flue of the same pair.
65. 9. In a coking oven, in combination: a series of alternate coking chambers and heating walls therefor arranged laterally of each other in a row; each of said heating walls comprising a row of combustion flues, the row of combustion flues in each of the heating walls being divided into units of at least one flue each and the units in each of the rows being communicably connected with the units in one of the other heating walls, respectively, for passage of combustion products from the flues of one unit into and 70 through the flues of the other unit by ducts individual to and communicably connecting one of said units in one of the heating walls with one of said units in one of the other heating walls, said ducts being so distributed along each of the rows of flues that gas flow may be controlled through each of the units in the respective rows for their respective positions therein independently of the gas flow through units in other positions in the same row therewith; and gas pressure 75 equalizing passages communicably connecting the respective duct-interconnected units with other duct-interconnected units which lie in relatively different positions in their respective rows, said equalizing passages being separate from and independent of the communications between the respective ducts and the flues with which said ducts communicate.
80. 10. The combination as defined in claim 9 and in which the heating walls are operatively disposed and interconnected in pairs by means of said ducts and in which other equalizing channels are provided between and in communication with the ducts of successive pairs of the duct-interconnected flue walls.
85. 11. In a coking retort oven, in combination: a series of alternate coking chambers and heating walls therefor arranged laterally of each other in a row, each of said heating walls comprising a row of combustion flues, the row of flues in each of the heating walls being divided into units of at least one flue each; the flues in one of the 90
95. 12. The combination as defined in claim 11 and in which the heating walls are operatively disposed and interconnected in pairs by means of said ducts and in which other equalizing channels are provided between and in communication with the ducts of successive pairs of the duct-interconnected flue walls.
100. 13. The combination as defined in claim 12 and in which the heating walls are operatively disposed and interconnected in pairs by means of said ducts and in which other equalizing channels are provided between and in communication with the ducts of successive pairs of the duct-interconnected flue walls.
105. 14. The combination as defined in claim 13 and in which the heating walls are operatively disposed and interconnected in pairs by means of said ducts and in which other equalizing channels are provided between and in communication with the ducts of successive pairs of the duct-interconnected flue walls.
110. 15. The combination as defined in claim 14 and in which the heating walls are operatively disposed and interconnected in pairs by means of said ducts and in which other equalizing channels are provided between and in communication with the ducts of successive pairs of the duct-interconnected flue walls.
115. 16. The combination as defined in claim 15 and in which the heating walls are operatively disposed and interconnected in pairs by means of said ducts and in which other equalizing channels are provided between and in communication with the ducts of successive pairs of the duct-interconnected flue walls.
120. 17. The combination as defined in claim 16 and in which the heating walls are operatively disposed and interconnected in pairs by means of said ducts and in which other equalizing channels are provided between and in communication with the ducts of successive pairs of the duct-interconnected flue walls.
125. 18. The combination as defined in claim 17 and in which the heating walls are operatively disposed and interconnected in pairs by means of said ducts and in which other equalizing channels are provided between and in communication with the ducts of successive pairs of the duct-interconnected flue walls.

heating walls on one side of one of said coking chambers being communicably connected for passage of combustion products to and through the flues in one of the heating walls on the opposite side of said coking chamber by a plurality of flow ducts extending transversely to and past said chamber, said ducts being disposed along the length of the respective rows of flues in said heating walls and being individual to and communicably connecting one of said units in one of said heating walls with one of said units in the other of said walls, respectively; and a gas pressure equalizing passage common to the flues of both of said walls and located in a plane of the coking chamber, said passage being separate from and independent of the communication between said ducts and the flues with which they communicate and directly communicably connecting the respective ducts with another duct spaced therefrom along the respective rows of flues in said heating walls at points in the flow ducts between the points at which the respective flow ducts communicate with the flue units that they respectively connect.

12. In a coking oven, in combination: a series of alternate coking chambers and heating walls therefor arranged laterally of each other in a row, each of said heating walls comprising vertical combustion flues, the flues of each of said heating walls being divided into units of at least one flue each; ducts individual to and communicably connecting one of said units in one of the heating walls at the top of said unit with one of said units in one of the other heating walls at the top of said unit; and equalizing passages extending through the tops of the vertical partition walls between adjacent vertical flues of adjoining units of flues in each heating wall and in communication with said flues at their upper parts but beyond the communication of the ducts with the flues of the units.

13. In a coking oven, in combination: a series of alternate coking chambers and heating walls therefor arranged laterally of each other in a row; each of the heating walls on opposite sides of one of said coking chambers comprising a row of vertical combustion flues divided into units of at least one flue each; a multiplicity of crossover conduits crossing the coking chamber and respectively communicably connecting one of said units in one of the heating walls on one side of the coking chamber at the top of said unit with one of said units in one of the the heating walls on the opposite side of the coking chamber at the top of said unit for passage of combustion products from the top of one of said units into the top of and through the other of said units; and gas pressure equalizing passages through the tops of the partition walls between and in communication with

the tops of adjacent flues of adjoining units of flues in each of said walls.

14. In a coking oven, in combination: a series of alternate coking chambers and heating walls therefor arranged laterally of each other in a row; each of the heating walls on opposite sides of one of said coking chambers comprising a row of vertical combustion flues; a multiplicity of cross-over ducts crossing over the coking chamber and communicably connecting the combustion flues in one of the heating walls on one side of the coking chamber at the tops of said flues with the combustion flues in one of the heating walls on the opposite side of the coking chamber at the tops of said flues, for passage of combustion products from the flues of one of said walls into the top of and through the combustion flues in the other of said walls; and gas pressure equalizing passages located above the levels of the tops of said combustion flues and respectively communicably connecting a plurality of the cross-over conduits which respectively communicably connect combustion flues in the heating wall on one side of the coking chamber with combustion flues in the heating wall on the opposite side of the coking chamber, said pressure equalizing passages being separate from and independent of the communication of the respective cross-over conduits with the combustion flues with which they respectively communicate.

15. In a coking oven, in combination: a series of alternate coking chambers and heating walls therefor arranged laterally of each other in a row; each of said heating walls comprising vertical combustion flues divided into units of at least one flue each; a multiplicity of cross-over ducts crossing over one of said coking chambers and respectively communicably connecting one of the units in one of the heating walls on one side of the coking chamber at the top of said unit with one of the units in one of the heating walls on the opposite side of the same coking chamber at the top of said unit for passage of combustion products from the units of one of said heating walls to and through the units of the other of said walls; separating partitions separating the respective communications in each heating wall of adjacent units with the cross-over conduits from each other for controlling gas flow for each unit independently of the other units in the same wall therewith; and gas pressure equalizing passages located above the levels of the tops of the combustion flues and respectively communicably connecting for gas pressure-flow the cross-over conduits for one of said units in one of said walls with the cross-over conduit for another of said units in the same wall therewith and that is separated therefrom by one of the aforesaid separating partitions.

16. In a coking retort oven battery com-

prising a series of alternate coking chambers and heating walls therefor arranged laterally of each other, with a row of vertical combustion flues in each of the heating walls, and with the vertical combustion flues in each of the heating walls communicably connected at their tops with the tops of vertical combustion flues in one of others of the heating walls, for off-flow of combustion products therethrough, by means of cross-over passages extending over the intervening coking chambers, and with the cross-over passages distributed lengthwise of the respective intervening coking chambers, for accommodating gas flow from vertical flues in different portions of each row of flues, respectively, the combination of gas pressure equalizing passages located above the levels of the tops of the combustion flues and respectively communicably connecting one of the cross-over passages for vertical flues in one portion of the battery relative to the length of the respective rows of flues with another cross-over passage for vertical flues in a relatively different portion of the battery relative to the length of the respective rows of flues, said equalizing passages being separate from and independent of the communication of the respective cross-over passages with the flues with which they respectively communicate.

17. In a coking retort oven battery comprising a series of alternate coking chambers and heating walls therefor arranged laterally of each other, with a row of vertical combustion flues in the respective heating walls divided into units of at least one flue each and with the units of the heating walls communicably connected at their tops with the tops of units in others of said heating walls, for off-flow of combustion products therethrough, by means of cross-over passages extending over intervening coking chambers and with said cross-over passages distributed lengthwise of the respective intervening coking chambers for accommodating gas flow from units in different portions of each row of vertical flues, respectively, and with separating partitions separating from each other the communication between the respective units and cross-over passages of adjacent units in each of said walls for controlling gas flow for each unit in each wall independently of other units in the same wall therewith, the combination of gas pressure equalizing passages located above the levels of the tops of the combustion flues and respectively communicably connecting for gas pressure flow the cross-over passage of one of said units in one of said walls with the cross-over passage for another of said units in the same wall therewith and separated therefrom by one of the aforesaid separating partitions.

In testimony whereof I have hereunto set my hand.

JOSEPH BECKER.
